UNITED STATES PATENT OFFICE.

HENRY C. MANNY, OF GRAYS RUN, PENNSYLVANIA.

LIFTING-JACK.

1,051,144.

Specification of Letters Patent. Patented Jan. 21, 1913.

Application filed July 12, 1911. Serial No. 638,148.

To all whom it may concern:

Be it known that I, HENRY C. MANNY, a citizen of the United States, residing at Grays Run, in the county of Lycoming and State of Pennsylvania, have invented certain new and useful Improvements in Lifting-Jacks, of which the following is a specification.

This invention relates to lifting jacks, and the principal object of the same is to provide simple means whereby adjustments are facilitated, and also for locking the parts of the jack in their adjusted position.

Preferred and practical embodiments of the invention are shown in the accompanying drawings, wherein—

Figure 1 is a perspective view of the improved jack. Fig. 2 is a central vertical sectional view. Fig. 3 is a horizontal sectional view.

Like references designate corresponding parts in the several figures of the drawings.

The improved lifting jack comprises a tubular support 4 having an enlarged base 5, and at one portion of its upper edge is provided with a laterally projecting boss 6 through which an opening 7 is formed, said opening communicating at an intermediate point with the interior of the support. Adjacent one end, a key opening 8 is formed through the boss 6 and intersects the opening 7. A locking bolt 9 is rotatable in the opening 7, and has a portion longitudinally and eccentrically cut away, as indicated at 10, to conform to the curvature of the interior of the support. The bolt 9 is provided with a circumferential groove 11 that is in alignment with opening 8, and a key 12 extends through opening 8 and engages groove 11 to prevent the bolt 9 having longitudinal movement in opening 7. Also the bolt 9 has an enlarged head 12, that projects beyond one end of the boss and is provided with a transverse opening in which an operating handle 13 is loosely mounted. The other end of the bolt 9 is flush with the adjacent end of boss 6, and the said adjacent ends are provided with indicators, or marks, 14 and 15 to designate the position of the cut-away portion 10 of said bolt relative to the interior of the support 4. Internally the support 4 is provided with a longitudinally arranged guiding rib 16. A hollow post 17 is vertically movable in the support 4, and is provided with an external longitudinally extending groove 18 with which the rib 16

interlocks to prevent relative rotation of the support and post. Externally the post 17 is provided with regularly spaced transverse keeper grooves 19 which are adapted to be selectively engaged by bolt 9 to lock the post against longitudinal movement relative to said post. The post 17 is internally threaded, and the externally threaded shank 20 of a work support 21 adjustably engages the same. The work-holder is provided with a central pivot stud 22 upon which a work rest 23 is rotatable. The rest 23 is provided with radiating grooves on its upper surface to present a roughened surface that prevents work slipping. The support 21 is provided with intersecting openings 24 through which the operating bar 25 extends. It will be clear from the foregoing that by rotating the eccentric locking bolt 9 to present its notched or cut-away portion 10 to the interior of the support 4, the post 17 can be moved vertically, and by rotating the said bolt to present its full rounded side within the support, the same will engage one of the grooves 19 and thereby lock the post against vertical movement. To facilitate the locking of the post 17 indication marks 26 are provided thereon to show when the grooves 19 are in position to be engaged by the solid part of the bolt 9.

It will be seen that this invention provides means whereby the work can be rotated while supported, and that two distinct adjustments may be obtained, one by adjusting the post 17 relative to the support 4, and the other by adjusting the work support 21 relative to said post.

What I claim as my invention is:—

1. A lifting jack comprising a hollow support having a boss provided with an opening which communicates with the interior of the support, a locking bolt rotatable in said opening and provided with a notched portion, a post vertically movable in said support and slidably interlocked therewith to prevent rotary movement of said post, regularly spaced transverse grooves being formed in said post that are selectively engaged by said bolt to prevent longitudinal movement thereof, a work support adjustably connected to said post, and means for rotating the locking bolt.

2. A lifting jack comprising a hollow support, a post longitudinally movable therein and provided with regularly spaced transverse grooves, an eccentric locking bolt

- extending transversely through one side of the upper portion of said support and adapted to selectively engage said grooves to prevent vertical movement of said post, means for rotating said bolt, and work supporting means carried by said post.
3. A lifting jack comprising a base support provided with a boss, a locking bolt rotatable therein and provided with a circumferential groove, a key extending through said boss and engaging said groove to prevent longitudinal movement of the bolt, a post longitudinally movable in the support and provided with means adapted to be engaged by said bolt to prevent longitudinal movement of said post, means for rotating said bolt, and work supporting means carried by said post.

4. A lifting jack comprising a hollow support, an eccentric locking bolt extending transversely across the upper portion thereof, a post longitudinally adjustable in said support and provided with grooves that are engaged by said bolt to lock the post to said support, said bolt and the upper portion of the support being provided with co-operating means to indicate the position of said bolt relative to the grooves of the post, and work supporting means adjustably connected to the post.

In testimony whereof I hereunto affix my signature in the presence of two witnesses.

HENRY C. MANNY.
